UNITED STATES PATENT OFFICE.

WILLIAM F. LA ROSE, OF ROCHESTER, NEW YORK.

AUTOMATIC FUEL-OIL VAPOR BURNER.

Application filed May 5, 1925. Serial No. 28,155.

This invention relates to liquid fuel burners, and consists of the novel construction and combination of parts hereinafter fully described and claimed, and illustrated in the 5 accompanying drawings, wherein:

Figure 1 is a view partly in elevation and partly in vertical section of a burner embodying my invention,

Figure 2 is a top plan view of the burner, 10

Figure 3 is a detail sectional view of the vaporizer on an enlarged scale,

Figure 4 is a detail top plan view of the fan or rotor of the vaporizer,

Figure 5 is a detail sectional view of the 15 burner on an enlarged scale, and

Figure 6 is a detail top plan view of the burner.

Corresponding and like parts are referred 20 to in the following description, and designated in the several views of the accompanying drawings, by similar reference characters.

The device comprises a draft flue or chamber 1 fully open at its upper end and provided in its base 2 with air inlet openings 3. A conduit 4 in communication with a motor driven fan 5 or other suitable source of air under pressure, extends into the draft flue 1, and connected to the inner end thereof is an elbow 6 which is supported by a stand 7 extending upwardly from the base 2. A mixing tube 8 provided with a venturi 9 is connected at its lower end to the elbow 6 and positioned upon the upper end 35 thereof is a burner 10.

The burner comprises a shallow cylindrical lower member 11 which rests on the upper end of the mixing tube 8 and which is provided with an opening 12 registering 40 with the bore of the mixing tube 8. The burner member 11 is secured in place by an annular flange 13 formed integrally therewith and embracing the upper end of the mixing tube 8. A concavo-convex screen 45 14 is secured in place over the upper end of the mixing tube 8 with its convex side disposed uppermost by means of the burner member 11. The upper burner member 15 is in the form of a circular plate which is 50 smaller in diameter than the internal diameter of the lower burner member 11 and which is provided with an upwardly offset central portion 16 having a concave lower side and a diameter greater than that of 55 the opening 12. The burner member 15 is supported above the bottom wall of the

lower burner member 11 and its edge maintained in inwardly spaced relation to the vertical wall of the lower burner member 11 by means of legs 17 which rest upon said 60 bottom wall in contact with said vertical wall. The burner member 15 is provided with a radial flange 18 which overlies and is spaced from the upper edge of the vertical wall of the burner member 11. 65

A tube 19 having its upper end positioned in the lower end of the mixing tube 8 and its lower end extending through and secured to the bottom wall of the elbow 6, constitutes part of an oil conduit 20 extending 70 from a float chamber 21. A pipe 22 extending from an oil storage tank is connected to the float chamber 21 as at 23, and the latter is provided with a drain cock 24.

A nozzle 25 is secured at its lower end to 75 the upper end of the tube 19, and is provided near its upper end with a restricted and axially arranged outlet port 26 and above said port with radially outlet ports 27. A horizontal plate 28 is carried by the 80 nozzle 25 directly below the outlet ports 27 and is provided with air passages 29. A shallow annular flange 30 extends upwardly from the plate 28 and a comparatively deep annular flange 31 extends downwardly from 85 the plate about the nozzle 25. A nipple 32 has threaded connection with the upper end of the nozzle 25 and mounted thereon is a fan or rotor 33. A spreader plate 34 is threaded to the nipple 32 above the fan or 90 rotor 33 and retains the latter in place and carries a needle valve 35 by means of which the size of the outlet port 26 may be regulated and controlled. The fan 33 comprises a hub 36, arms 37 extending radially from 95 the hub, and downwardly extending blades 38 arranged at an angle with respect to the axis of the fan or rotor.

In practice the float chamber 21 is so arranged that the normal level of the fuel oil 100 in the tube 19 will be just below the port 26 of the nozzle 25. During the operation of the device the fan 5 will force air through the conduit 4, elbow 6, and into the lower end of the Venturi mixing tube 8. During its passage through the Venturi tube 8 the air will pass about the parts 28, 33 and 34 and through the openings 29 against the blades 38 of the fan or rotor 33 with the result that the rotor 33 will be set in motion and oil drawn up through the port 26 and laterally through the ports 27. The 105 110

rotor 33 produces an intimate mixture of the oil and air so that the former is thoroughly vaporized before entering the venturi 9. The vaporized oil and air will be more thoroughly commingled during their passage through the venturi 9 due to the fact that their rate of travel is materially increased by the venturi 9. The combustible mixture thus formed will pass through the screen 14 and out through the lateral side of the burner 10. The construction of the burner 10 is such that the flame is spread over a large area. A pilot 39 is provided for the purpose of igniting the combustible mixture, and while this pilot is shown as a gas pilot it may be of the electrical type. The device is of such construction that it may be controlled by any of the many well known thermostats now on the market. A drain pipe 40 extends from the bottom of the elbow 6 to a trip valve, not shown, in the supply pipe 22.

From the foregoing description, taken in connection with the accompanying drawings, the advantages of the construction and of the method of operation of the device will be readily apparent to those skilled in the art to which it appertains.

While I have described the principle of operation of the device, together with the structure which I now consider to be the best embodiment thereof, I desire to have it understood that the device shown is merely illustrative, and that such changes may be

made when desired as are within the scope 35 of the invention as claimed.

What is claimed is:—

1. A device of the character set forth, comprising a Venturi mixing tube, piping of which said tube forms a part, a burner associated with one end of the tube, means for supplying air through the pipe to the other end of the tube, a nozzle entering said other end of the tube, a plate secured to the nozzle and located within the tube, said plate having an opening communicating with the nozzle and provided laterally beyond said opening with air passages, a fan rotatably supported above the plate, and means for supplying liquid to the nozzle. 50

2. A device of the character set forth, comprising a Venturi mixing tube, piping of which said tube forms a part, a burner associated with one end of the tube, means for supplying air through the pipe to the other end of the tube, a nozzle entering said other end of the tube, a plate located within said other end of the tube and secured to the nozzle, said plate having an opening communicating with the nozzle and provided with air passages, a spreader supported above said plate, a rotatably mounted fan positioned between the plate and spreader, and means for supplying liquid to the nozzle. 60 65

In testimony whereof I affix my signature.

WILLIAM F. LA ROSE.
